Primary Examiner — Karen S Acker*(74) Attorney, Agent, or Firm* — Cozen O'Connor(57) **CLAIM**

I claim the ornamental design for a tissue sheet with applied pattern, as shown and described.

DESCRIPTION

The sole FIGURE is a plan view of the tissue sheet with applied pattern.

The broken lines surrounding the tissue sheet with applied pattern represent the boundaries of the claim and form no part thereof. The broken lines within the boundaries represent unclaimed environmental subject matter and form no part of the claimed design.
